ROBERT K. WINNING, OF MILWAUKEE, WISCONSIN, ASSIGNOR TO CLUM MANUFACTURING COMPANY, OF MILWAUKEE, WISCONSIN.

ROTARY SWITCH.

Application filed July 16, 1924. Serial No. 726,269.

This invention relates to improvements in electric switches of the rotary type.

It is the primary object of this invention to provide a novel and simplified construction of full floating switch contact and operating member.

It is a further object of this invention to provide a device having few parts and adapted for economy of manufacture while preserving nevertheless a sturdiness of construction ensuring long life and satisfactory operation.

In the drawings:

Figure 1 is a fragmentary transverse section through a switch casing embodying an electrical switch mechanism incorporating this invention.

Figure 2 is a section taken on line 2—2 of Figure 1.

Figure 3 is a detail view taken on the section indicated at 3—3 in Figure 2.

Figure 4 is a detail view taken on the section indicated at 4—4 in Figure 3.

Figure 5 is a detail view in side elevation of the switch operating member.

Like parts are identified by the same reference characters throughout the several views.

The switch casing will be described but briefly since its construction forms no part of the particular invention to be claimed in this application. The particular casing illustrated is adapted to contain more than one switch and includes a body member 10 comprising the side wall of the casing and stamped to provide a recess 11 in which the switch hereinafter to be described is disposed. An integral flange 12 is connected by bolts or screws, such as that indicated at 40 13, with a fiber back 14 in which are embedded suitable metallic contact bushings 15 and 16 which comprise terminals for an electric circuit to be controlled by the switch. Equidistant between the terminals 15 and 16 is a pin 17 knurled at 18 and projecting inwardly into the casing. Spot-welded or otherwise fastened as at 19 to a flange 20 on the casing wall 10 is a disk 21 apertured at 22. A bezel 23 retains a glass finishing plate 24 in contact with a backing 25. The bezel is provided with a tongue 27 bent about the peripheral margin of the disk 22 to hold the parts in assembled relation. The same func-

tion is performed also by means of a bushing 29 made in the form of an eyelet and upset at 30 and 31 to overlie respectively the glass plate 24 and the disk 22.

The switch actuating member comprises a short length of shaft 35 journaled in the bushing 29. The shaft is peripherally grooved at 37 to provide a portion of reduced diameter, beyond which there is a knurled head 38 adapted to be grasped by the fingers of an operator. The knurled head is of the same or slightly less diameter than the shaft 35 and is integrally formed therewith.

Upon the shaft I provide an integral collar 40 beyond which projects a switch actuating head 41 and supporting shoulders 42. The head is rectangular in cross section, as is shown in Figure 2, and is thereby adapted for engagement in a correspondingly formed aperture in the floating contact hereinafter to be described. The rectangular form of the head is adapted to key the switch actuating member to the floating contact and thereby to transmit rotative movement from the member to the contact. Any other cross sectional form adapted to perform this function may be substituted for the rectangular shape illustrated.

The shoulders 42 are shaped, as best indicated in Figure 3, to provide a fulcrum for the floating contact. To this end they have high points at 43 in a common transverse axial plane, and from these high points the shoulders slope to either side. It is obviously immaterial whether the slope takes the form of the curve illustrated but the illustrated construction is preferred.

For reasons hereinafter to be specified, head 41 is preferably also curved at its extremity to provide a transversely extending cylindrical surface as at 44. The head is provided with an axial aperture at 45 into which projects the pin or stud 17. The stud serves in conjunction with the bushing 29 to provide a bearing support for the purpose of centering and rotatively mounting the shaft 35. The pin 17 preferably does not extend to the bottom of recess 45 and therefore does not interfere with the resilient mounting of the switch actuating member.

A washer 47 encircles shaft 35 and rests against the upset portion 31 of bushing 29.

Confined between said washer and the integral annular flange 40 of shaft 35 is a compression spring 48 which urges the entire switch actuating member in the direction of the fiber back plate 14. Its movement in that direction is opposed only by the floating switch contact now to be described.

The floating switch contact comprises a fiber disk 50 with a rectangular opening at 51 to fit the head 41, as shown in Figure 3.

The disk is fulcrumed upon the shoulder 43 which transmits to it the pressure of spring 48. Upon one face of the disk is a thin metal plate 55 having ears 56 bent about the disk to retain the plate in position thereon. The disk is preferably provided with notches 57 in its periphery to receive the ears 56 whereby to secure the plate 55 against rotation relative to the fiber disk.

20 The plate 55 may be generally of a circular form, as shown, and is provided with a large central aperture 59 affording clearance for the head 44, with which it is undesirable to make electrical contact. Aperture 59 is; 25 therefore, slightly larger than the aperture 51 in fiber disk 50.

30 The disk 55 is provided integrally with contact members in the form of protuberances 60 which may conveniently be formed by a stamping operation. These contact members are spaced apart the same distance as the metallic sleeves 15 and 16 in the back plate of the switch so that in one position of rotation of the floating contact the convex 35 surfaces of the protuberances 60 will ride into and be partially received within the open ends of the terminal sleeves 15 and 16. Thereby an electrical circuit will be completed between terminals 15 and 16 through 40 the protuberances 60 and the metallic plate 55. The plate, however, is wholly insulated by its mounting on fiber disk 50 from all metallic surfaces other than the terminal members 15 and 16.

45 Obviously, if the knurled knob 38 is turned to rotate shaft 35 the rotative movement thereof will be transmitted through head 41 to the floating contact just described, and such contact will be caused to rotate. 50 Initially the contact and the entire switch actuating shaft 35 will have an axial movement against spring 48 in order to permit the convex protuberances 60 to rise out of the terminal members 15 and 16 in which 55 they rest when the switch is closed. As soon, however, as the contacts 60 have left the terminals they will ride over the surface of the fiber back plate 14 to any desired rotative position. This type of switch, however, is well-known and needs no further description.

60 In driving the terminal members 15 and 16 into the fiber back plate 14 of the switch it is conceivable that such members may not 65 be perfectly flush with the surface of plate

14 upon which the floating contact rides. Furthermore, it is conceivable that the entire back plate 14 may be out of parallelism with the front face of the switch, or that some other conditions may obtain such as to prevent the shaft 35 from being in its usual position normal to the back plate 14. To make the switch perfectly operative in any such contingency so that the pressure of spring 48 may be transmitted alike to both 70 of the contacts 60 of the rotary switch member, the said member is fulcrumed as above described for oscillation on an axis transverse with respect to a line drawn between the two protuberances or contacts 60. Thus, 80 regardless of any possible slight irregularities in the construction of the switch the pressure of spring 48 will always be transmitted to the moving contact in such a manner as to force such contact to adapt itself 85 to the surfaces over which it operates. It will be noted that to accomplish this result I have provided a floating contact which is movable axially and rotatively and may be oscillated on a transverse axis, but which is secured against any tilting movement on an axis joining the protuberances 60. If such tilting movement were possible, the said portions of plate 55 which connect contacts 60 to each other might touch the terminals 15 or 16 to the possible detriment of the switch. The floating contact is therefore supported against such tilting movement by means of the laterally spaced shoulders 42.

85 The floating contact is likewise secured 100 against radial movement in any direction. Thereby the contacts 60 are maintained invariably in a position for registry with the terminals 15 and 16.

It will be noted that the actuating shaft 35 requires nothing to maintain it properly positioned within its bearing other than the reaction of spring 48, which furnishes the necessary pressure for the switch contacts. The pin or stud 17 supports and positions shaft 35 and is engaged in the aperture 45 thereof when the back plate 14 is set in place. In the normal operation of the device, however, pin 17 does not limit the axial movement of the shaft. If it did, it would prevent the 115 contacts 60 from receiving the pressure of spring 48.

120 It will be noted that the entire device is very simply constructed and is easily assembled. The spring 48 and washer 47 are assembled on shaft 35 and the shaft is then thrust through the bushing 29 in which it finds a bearing. As previously explained, the knurled head 38, by which the device is 125 manually grasped for operation, is no larger in diameter than the shaft so that this method of assembly is facilitated. The floating contact is now positioned on the head 41 and the back plate 14 is attached to the casing member 10 in such fashion that the pin 17 130

is received within aperture 45 of the shaft. This completes the assembly of the switch and leaves it operative.

In the event that the floating contact is caused to oscillate about its fulcrum on shoulders 42 during the operation of the switch, the head 41 which transmits rotative movement to the floating contact might bind in the aperture 51 of fiber disk 50 if it were not for the fact that the said head 41 is provided with a cylindrically rounded surface 44 which affords clearance for any conceivable oscillation of the floating contact on its fulcrum mounting.

15 I claim:

1. In a device of the character described, the combination with a rotor providing a fulcrum relatively fixed with reference to the rotor, of a dielectric member bearing on said fulcrum, and an electrical contact carried by said member.

2. In a device of the character described, the combination with a rotor provided with means defining a transverse fulcrum, of a di-electric member bearing against the fulcrum of the rotor, and an electrical contact carried by said member at one side of the axis upon which said member is fulcrumed.

3. In a device of the character described, the combination with a rotor and a spring arranged to urge said rotor axially, of a floating contact member fulcrumed to said rotor on an axis transverse with respect thereto and held to its fulcrum by the pressure of said spring transmitted through said rotor.

4. In a device of the character described, the combination with a rotor and a spring urging said rotor axially, a contact-carrying member provided with a fulcrum bearing on said rotor and splined thereto for rotation therewith, contacts on said members spaced upon either side of the fulcrum thereof, and means providing relatively stationary contacts adapted for interaction with the contacts carried by said member, said member being forced to a position for interaction with said stationary contacts through the pressure of said spring transmitted through said rotor and the fulcrum bearing of said member on said rotor.

5. In a device of the character described, the combination with a switch casing having a back plate provided with relatively fixed contacts and having a front plate provided with an aperture, of a switch actuating rotor extending through said aperture and provided with aligned fulcrum members upon either side of its axis, a spring urging said rotor toward said back plate, and a contact element confined between said fulcrum member and said back plate and operatively connected with said rotor for rotation therewith, said contact element being provided with contacts adapted in one position of ro-

tation thereto to register with the contacts of said back plate.

6. In a device of the character described, the combination with a switch casing having a back plate provided with relatively fixed 70 electrical terminals and having an apertured front plate, of a rotor extending through said front plate, a spring urging said rotor axially in the direction of said back plate, said rotor being formed to provide a fulcrum transverse with respect to its axis, and a contact carrying member confined between said fulcrum and said back plate and including contacts adapted in one 75 position of rotation for registry with the terminals of said back plate.

7. In a device of the character described, the combination with a contact member including a di-electric support and electrical contacts carried thereby, of a rotor including 80 a centrally disposed head in splined relation to said support, and a shoulder on either side of said head providing a fulcrum for said support, the splined connection between said head and the support being such as to 85 permit said support to oscillate on said fulcrum.

8. In a device of the character described, the combination with an apertured switch casing, of a switch actuating member comprising 95 a shaft adapted to fit within the aperture of said casing and provided with an exposed manually engageable portion receivable through said aperture, and means formed integrally with said shaft adapted 100 for the support of a floating switch contact and the operative rotation thereof.

9. In a device of the character described, the combination with an apertured switch casing, of a switch actuating member comprising 105 a shaft adapted to fit within the aperture of said casing, and having an manually engageable portion receivable through said aperture; a contact member within said casing in splined relation to said shaft; and means rigidly connected with said shaft providing 110 a fulcrum bearing for said member upon which said member is adapted to oscillate while maintaining its splined connection with the shaft.

10. In a device of the character described, the combination with an apertured switch casing, of a switch actuating member comprising a shaft adapted to fit within the aperture of said casing and having a manually 115 engageable portion receivable through said aperture, a contact member within said casing in splined relation to said shaft, means rigidly connected with said shaft providing a fulcrum bearing for said member upon which said member is adapted to oscillate while maintaining its splined connection with the shaft, a pair of contacts supported from said member in operative electrical connection with each other and insulated from 120 125 130 135

said shaft, and a set of electrical terminals mounted in said switch casing and arranged operatively for registry with said contacts in one position of rotation of said shaft and said member.

11. In a device of the character described, the combination with a switch casing having an apertured face and a set of electrical terminals at its back at substantially equal radial distances from the projected axis of said aperture, of a rotor comprising a shaft projecting through said aperture and provided within said casing with a centrally disposed head and shoulders upon either side of said head providing an open fulcrum bearing, a spring confined between a portion of said shaft and the front of said casing, whereby to urge said shaft axially toward the rear of said casing, and a floating electrical contact member provided with contacts adapted for registry with the terminals of said casing, said member being confined between said shoulders and back of said casing.

12. In a device of the character described, the combination with a switch casing having an apertured face and a set of electrical terminals at its back at substantially equal radial distances from the projected axis of said aperture, of a rotor comprising a shaft projecting through said aperture and provided within said casing with a centrally disposed head and shoulders upon either side of said head providing an open fulcrum bearing, a spring confined between a portion of said shaft and the front of said casing, whereby to urge said shaft axially toward the rear of said casing, a floating electrical contact member provided with contacts adapted for registry with the terminals of said casing, said member being confined between said shoulders and the back of said casing and comprising a di-electric support resting on said shoulders and splined to said head, and a metallic face plate attached to said support and provided with integral protuberances constituting electrical contacts.

13. In a device of the character described, a switch actuating member comprising a shaft, a head of generally rectangular cross section and terminating in a surface rounded about a transverse axis, said head being disposed centrally of said shaft, and shoulder members formed integrally with said head upon either side thereof and having terminal portions rounded upon a common

transverse axis substantially in the plane of said first mentioned axis.

14. In a device of the character described, the combination with a contact member providing a central opening, of an actuating rotor including a head conforming to said opening and adapted to be fitted therein, and a pair of shoulders on opposite sides of said head provided with terminal surfaces rounded upon a common transverse axis.

15. In a device of the character described, the combination with a floating switch contact comprising a di-electric support provided with a central aperture, and a metallic face plate connected with said support and carrying interconnected electrical contacts, of an actuating member including a shaft having a terminal portion splined within the aperture of said di-electric support and a pair of shoulders upon either side of said terminal portion integrally connected therewith, said shoulders providing a transverse fulcrum for said di-electric support.

16. In a device of the character described, the combination with a switch casing having a bearing aperture, of a rotor journaled in said aperture and provided with an exposed manually engageable portion receivable therethrough, a spring acting upon said rotor in a direction to press it centrally of said casing from said aperture, a contact member connected with said rotor to receive rotation therefrom, and a terminal supported by said casing in a position to be contacted by said member, said casing being so formed with reference to the length of said rotor and of said spring as to maintain said spring under compression when said member is in contact with said terminal.

17. In a device of the character described, the combination with a casing having separable front and rear faces and a bearing aperture in its front face, of a rotor journaled in said aperture and having a manually engageable portion projecting therefrom, a spring confined between a portion of said rotor and the front face of the casing whereby to press said rotor rearwardly, and a contact member operatively adjustable with reference to the rear face of the casing and interposed between the rear face and the rotor under the compression of said spring, the separation of said front and rear faces being adapted to permit the removal of the rotor through said aperture.

ROBERT K. WINNING.
